(57) **CLAIM**

The ornamental design for a gaming machine computer betting display screen with graphical user interface, as shown and described herein.

DESCRIPTION

FIG. 1 is a front view of a gaming machine computer betting display screen with graphical user interface of one embodiment of my new design; and, FIG. 2 is a front view of a gaming machine computer betting display screen with graphical user interface of another embodiment of my new design.

The outermost broken lines illustrate a gaming machine computer betting display screen, and forms part no of the claimed design. The remaining broken lines illustrate portions of the graphical user interface that form no part of the claimed design.

1 Claim, 2 Drawing Sheets
